(57) **CLAIM**

The ornamental design for a cutting device for fruit juicer, as shown and described.

DESCRIPTION

FIG. 1 is a perspective view of cutting device for fruit juicer showing my new design;
FIG. 2 is a front elevational view thereof;
FIG. 3 is a rear elevational view thereof;
FIG. 4 is a left side elevational view thereof;
FIG. 5 is right side elevational view thereof;
FIG. 6 is a top view thereof; and,
FIG. 7 is a bottom view thereof.
